SNUBBED TRUCK

Carl E. Tack, Chicago, Ill., assignor to American Steel Foundries, Chicago, Ill., a corporation of New Jersey

Application September 27, 1947, Serial No. 776,603

11 Claims. (Cl. 105—197)

1

This invention relates to railway car trucks and more particularly to a friction device for damping oscillations of the truck bolster which supports the car body.

In the prior art various trucks have been proposed and a number have been placed in service wherein bolster oscillations are damped by friction devices associated with the bolster for developing friction to resist its oscillations. Such arrangements have been generally successful in eliminating harmonic action of the bolster-supporting springs and the resultant harmful effect well known to those skilled in the art. However, one fault inherent in all such devices heretofore proposed in the transmission of vibrations from the truck frame to the bolster and the structure supported thereby, due to the fact that the static friction developed in devices such as those heretofore used for damping purposes is relatively great in order to afford satisfactory kinetic friction to prevent harmonic oscillations of the bolster-supporting springs.

In other words, in prior art arrangements, whether the friction device has been mounted on the frame for cooperation with the bolster or has been mounted on the bolster for cooperation with the frame, severe vibrations have been transmitted from the frame to the bolster during periods when the bolster has been static relative to the frame. This phenomena has been due to the relatively great coefficient of static friction inherent in such arrangements to afford satisfactory kinetic coefficient of friction. Reduction of the static coefficient of friction has heretofore been regarded as impossible due to the consequent reduction of the kinetic coefficient to a useless value.

Accordingly, a primary object of the present invention is to afford a friction device for damping oscillations of a railway car truck bolster at a lower static coefficient of friction than has heretofore been possible.

Another object of the invention is to afford a friction device, such as above-described, having a static coefficient of friction not substantially greater than the kinetic coefficient to afford satisfactory damping of bolster oscillations at all times.

Still another object of the invention is to reduce transmission of vibrations from the frame to the bolster by affording means for absorbing such vibrations and also capable of developing a sufficient kinetic coefficient of friction to afford satisfactory damping of bolster oscillations.

Still another object of the invention is to pro-

2

vide a friction device, such as above-described, wherein the static and kinetic coefficients of friction are substantially equal to accommodate damping of the bolster oscillations at a uniform coefficient of friction throughout the bolster stroke.

The foregoing and other objects and advantages of the invention will become apparent from a consideration of the following specification and the accompanying drawings, wherein:

Figure 1 is a fragmentary side elevation of a car truck embodying the invention;

Figure 2 is a sectional view on the line 2—2 of Figure 1 with the bolster shown in side elevation;

Figure 3 is a fragmentary top plan view of the bolster and associated friction devices with the side frame shown in section through the columns thereof;

Figure 4 is a sectional view on the line 4—4 of Figure 3;

Figure 5 is a sectional view on the line 5—5 of Figure 3;

Figure 6 is a fragmentary side elevational view of a railway car truck embodying a modification of the invention;

Figure 7 is a sectional view of the line 7—7 of Figure 6 with the bolster shown in side elevation;

Figure 8 is a fragmentary top plan view of the bolster shown in Figures 6 and 7 with the side frame shown in section through the columns thereof;

Figures 9 to 14, inclusive, illustrate the novel friction shoe utilized in the arrangement of Figures 6 to 8, Figure 9 being a front elevational view of the shoe, Figure 10 being a side elevational view thereof, Figure 11 being a rear elevational view, Figure 12 being a fragmentary top plan view, Figure 13 being a fragmentary bottom plan view, and Figure 14 being a fragmentary sectional view on the line 14—14 of Figure 10;

Figures 15 to 18 illustrate a modification of the shoe utilized in the arrangement of Figures 6 to 8, Figure 15 being a side elevational view of the shoe, Figure 16 being a rear elevational view, Figure 17 being a fragmentary top plan view, and Figure 18 being a fragmentary bottom plan view; and

Figure 19 is a side elevational view of another modification of the shoe utilized in the arrangement of Figures 6 to 8.

One embodiment of my novel truck arrangement is shown in Figures 1 to 5 inclusive, wherein the side frame, generally designated 2, comprises tension and compression members 4 and 6

merging adjacent corresponding ends thereof with columns 8 defining therewith the bolster opening 10 with widened upper portion 12 (Figure 1). The tension member beneath the bolster opening is a box section with the inboard and outboard webs 14 and 16 and the top and bottom chords 18 and 20 as well as the vertical reinforcing rib 22 disposed intermediate the walls 14 and 16. The top chord 18 is widened and formed with upstanding inboard and outboard flanges 24 and 26 defining a spring seat 28 upon which are seated a plurality of coil springs 30 affording support for the bolster, generally designated 32.

The bolster comprises the top and bottom walls 34 and 36 and the spaced side walls 38, and a pocket 40 is formed in each side of the bolster, said pocket being defined in part by the inboard and outboard walls 42 and 44 offset respectively at 46 and 48 and merging with a rear wall 50 at the inner end of the pocket. Integrally formed with the inboard and outboard walls 42 and 44 are the spaced ledges 52 and 54, said ledges presenting wedge surfaces sloping upwardly and outwardly toward the adjacent column and engaged at 56 and 58 respectively with wing portions 60 and 62 of a friction shoe, generally designated 64, said shoe comprising a top wall 66 affording a seat 68 for the upper end of a spring 70, the lower end of said spring being seated at 72 against the bottom wall 36 of the bolster.

Each friction shoe 64 also comprises a front wall 74 for engagement at 76 with a wear plate 78 mounted on the adjacent column 8. The wear plate is preferably one which has substantially the same static coefficient of friction as the kinetic coefficient. Such a material having the following composition may be obtained by conventional curing at about 325° F. and under adequate pressure to produce the desired density:

Material	Parts by Weight
Rubber	4.5
Phenolic Formaldehyde Resin	5.0
Cashew Nut Shell Polymer	3.0
Graphite	7.0
Bakelite Impregnated Asbestos Wire Reinforced Yarn	70.0
Carbon Black	2.0
Barium Sulphate	7.5
White Lead	7.5

Another such material is disclosed in United States Letters Patent No. 2,052,779, issued September 1, 1936, to Harvey J. Lidke and Ray E. Spokes. It will be understood that any desired friction material may be utilized wherein the static coefficient of friction is not appreciably greater than the kinetic coefficient and preferably where they are substantially equal.

Each shoe also comprises a rear wall 80 offset at 82 to form a handlelike loop received within a complementary offset 84 in the rear wall 50 of the pocket 40, the loop 82 being aligned with openings 86 in the inboard and outboard walls 42 and 44. It will be understood that a tool may be inserted into the openings 86 and may be engaged with the offset portion 82 of the wall 80 whereby the shoe may be withdrawn from engagement with the associated wear plate 78 during assembly and disassembly of the bolster and side frame.

As may be seen in Figures 1 and 5, the surfaces on the shoes are crowned from top to bottom thereof. It may also be noted that the bolster 32 comprises inboard and outboard guide lugs 88 and 90 at each side thereof for engagement with the inboard and outboard surfaces of the adjacent

column 8, the outboard lugs 90, as may be clearly seen in Figure 1, being of less depth than the widened portion 12 of the bolster opening, whereby the bolster may be elevated therein and removed therefrom during a quick wheel change without disturbing the supporting springs 30.

Figures 6 to 8 show another embodiment of the invention wherein the constant coefficient friction material is carried by the shoe. In this embodiment the truck is generally similar to that shown in Figures 1 to 5 and comprises a side frame, generally designated 102, and a bolster 104 supported therefrom by springs 106 adjacent a column 108 integrally formed with the frame adjacent each end thereof to define a bolster opening 110 (Figure 6).

The bolster, as in the previously described embodiment, is a box-section member with a pocket 112 in each side thereof containing spaced wedge surfaces 114 sloping downwardly from the adjacent column and engaging complementary wedge surfaces of a friction shoe, generally designated 116, actuated by a spring 118 seated on the bottom wall of the bolster.

The friction shoe 116 is shown in detail in Figures 9-14 wherein it will be seen that the shoe comprises a front wall 120 with a narrow upwardly extending projection 122 merging with a top wall 124 affording a seat on its under side for the before-mentioned spring 118. The rear end of the top wall 124 is integrally formed with a diagonal rear wall 126 having at its lower extremity an inturned portion 128 (Figure 10) defining a loop or socket 130 to afford convenient means for keying the shoe within the bolster, as described in connection with the embodiment of Figures 1 to 5.

At each side thereof the shoe 116 is formed with a diagonal wall or ledge 132 connected at its upper end to the front wall 120 and to a gusset 134 (Figure 10) formed with the top wall 124. The ledges 132, as will be understood by a consideration of Figures 6 and 8, are engageable with the complementary wedge surfaces 114 of the bolster. Each diagonal wall 132 is connected at its lower end to the inturned portion 128 of the rear wall 126 which is formed with a gusset 136 at each side thereof reinforcing its connection to the ledge 132. Each ledge 132 is connected to the front wall 120 by a side wall 138 reinforced by a gusset 140.

A friction liner 142 is secured to the front surface of the wall 120 and is provided with spaced lugs 144 received within complementary openings in the wall. The liner 142 is preferably formed of a constant coefficient friction material, such as that described in connection with Figures 1 to 5, and is bonded to the wall 120 by any desired thermal setting cement.

Referring again to Figures 6 to 8, it may be noted that the above-described construction of the friction shoe is such that the shoe-actuating spring 118 is seated against the spring seat wall 124 of the shoe at a point above the top wall 65 of the bolster 104, thereby affording a spring of maximum capacity. This feature, as above-noted, is accommodated by the extension 122 of the front wall 120 of the shoe.

Referring now to Figures 15 to 18, a modified friction shoe, generally designated 150, is illustrated for use in connection with the arrangement of Figures 6 to 8. The shoe 150 comprises a front wall 152 having an upwardly extending projection 154 integrally formed with a top wall 156 affording a seat on its under side for the

shoe-actuating spring 118. The top wall 156 is connected to a rear wall 158 having an offset portion 160 defining a loop or socket 162 for reception of associated key means, as heretofore described. The wall 158 is connected to spaced diagonal walls or ledges 164 which are connected by side walls 166 to the front wall 152. A friction face or liner 168 preferably of constant coefficient friction material, such as that above described, is secured to the front wall 152 and comprises an upwardly extending projection 170 complementary to the projection 154 of the shoe. The projection 170 is secured by a bolt 172 threaded into the projection 154 and the portion of the top wall 156 joined thereto. Beneath the bolts 172 are a pair of bolts 174 threaded through the front wall 152 and into the ledges 164 adjacent the upper extremity thereof. Beneath the bolts 174 are a pair of bolts 176 threaded through the front wall 152 and into the side walls 166. It may be noted that by means of the above-described arrangement the friction face 168 is securely bolted to the shoe 150 by stud bolts passing through relatively thick sections of the shoe particularly designed to accommodate this means of securing. Furthermore, the friction face 168 is coextensive with the entire front wall 152 including the extension 154 thereof, thereby affording a somewhat greater friction area than in the previously described shoe 116.

Figure 19 shows another modification of a friction shoe designed for use in the arrangement of Figures 6 to 8. The modification of Figure 19 is substantially identical with that shown in Figures 9 to 13 and corresponding parts are identified by corresponding numerals. In Figure 19, each ledge 132 is recessed as at 200 to receive a wedge face or liner 202 of constant coefficient friction material, such as that above described, the liner 202 having lugs or bosses 204 projecting in the complementary socket within the ledge 132 and being bonded thereto with any desired thermal setting cement.

It may be noted that the modification of Figure 19 is substantially identical with that of Figures 9 to 14 except for the provision of the wedge face 202 having a static coefficient of friction not greater than the kinetic coefficient of friction and preferably about equal thereto for the purpose of preventing sticking of the shoe along the associated bolster wedge faces as sometimes occurs due to the relatively high static coefficient of friction at that point where the wedge face 202 is not utilized. It will also be understood that friction developed against the wedge face 202 during oscillations of the bolster laterally thereof between the side frame columns is substantially constant.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. A railway car truck comprising a side frame member with a column, a bolster member spring-supported adjacent said column, said bolster member comprising top and bottom walls and spaced walls defining therewith a box section, a pocket in the bolster comprising a wedge surface sloping toward said column, a friction shoe actuator in said pocket in wedge engagement with said surface, said actuator comprising a spring

5 seat disposed a substantial distance above the level of said top wall, spring means seated against the bottom wall and against said seat for urging said actuator along said surface toward said column, and friction shoe means carried by the actuator in engagement with the friction surface on said column, the kinetic coefficient of friction between said surfaces and said shoe means being at least as great as the static coefficient.

10 2. A railway car truck comprising a supporting frame member, spring means carried thereby, another member supported by said spring means, and friction means for damping relative vertical movement between said members comprising a friction surface fixed with respect to one of the members, another friction surface carried by the other member, and actuating means for urging said other surface into engagement with the first-mentioned surface, said actuating means comprising spring means carried by one of the members and operatively connected to said other surface, the surface of one member being formed of material having a static coefficient of friction when engaged with the surface of the other member not substantially greater than the kinetic coefficient of friction of said material when engaged with the last-mentioned surface, and said surfaces being the sole means under normal conditions for frictionally resisting relative vertical movement between said members.

15 3. A railway car truck comprising a side frame member with spaced columns, a bolster member spring-supported between said columns, and friction means at each side of said bolster member comprising a pair of friction surfaces carried by the bolster member and the adjacent column respectively, wedge means interposed between one of said surfaces and the related member in wedge engagement with the latter, and spring means 20 carried by one of the members under compression against said wedge means for urging said surfaces into engagement, one of said surfaces being formed of material having a static coefficient of friction when engaged with the other surface not substantially greater than the kinetic coefficient of friction of said material when engaged with said other surface.

25 4. A truck, according to claim 3, wherein the wedge engagement of said wedge means and the related member is along surfaces, one of which is formed of material having a static coefficient of friction when engaged with the other surface not substantially greater than the kinetic coefficient of friction of said material when engaged with said other surface.

30 5. A railway car truck comprising a side frame with a column member, a bolster member spring-supported adjacent said column member, and friction means comprising a wedge in wedge engagement with one of said members along corresponding wedge faces having a static coefficient of friction not substantially greater than their kinetic coefficient of friction, said wedge and the other member having engaged friction surfaces, one of which is formed of material having a static coefficient of friction when engaged with the other surface not substantially greater than the kinetic coefficient of friction of said material when engaged with said other surface.

35 6. A railway car truck comprising a side frame member with a column member, a bolster member spring-supported adjacent said column member, and friction means comprising a wedge in wedge engagement with one of said members along corresponding wedge faces having a static coefficient of friction not substantially greater than their kinetic coefficient of friction, said wedge and the other member having engaged friction surfaces, one of which is formed of material having a static coefficient of friction when engaged with the other surface not substantially greater than the kinetic coefficient of friction of said material when engaged with said other surface, and spring means carried by one of said members for actuating the wedge.

40 7. A railway car truck comprising a frame member, a bolster member spring-supported therefrom, and friction means for damping relative vertical movement between said members

comprising a friction surface fixed with respect to one member, and a friction surface carried by the other member, one of said surfaces being formed of material having a static coefficient of friction when engaged with the other surface not greater than the kinetic coefficient of said material when engaged with said other surface, said surfaces being the sole means under normal conditions for frictionally resisting relative vertical movement between said members, and means for urging said surfaces into engagement.

7. A railway car truck comprising a side frame, a bolster spring-supported thereby, a wedge face on the bolster sloping toward a friction surface on said frame, a friction shoe engaging said face and having a friction surface engaging said frame surface, and spring means carried by the bolster and engaged with said shoe for actuation thereof, one surface being formed of material having a kinetic coefficient of friction, when engaged with the other surface, at least equal to the static coefficient of friction of said material when engaged with said other surface.

8. A railway car truck comprising a side frame member with a friction surface, a bolster member spring-supported by said side frame member, a wedge face on said bolster member sloping toward said friction surface, a friction shoe engaging said face and having a friction surface engaging said frame surface, and spring means compressed between one of said members and said shoe for actuation of the latter, one of said surfaces being formed of material having a kinetic coefficient of friction, when engaged with the other surface, not substantially less than the static coefficient of friction of said material when engaged with said other surface.

9. A railway car truck comprising a side frame member, a bolster member spring-supported by said frame member, a friction shoe, said frame member and shoe having a pair of engageable friction surfaces, respectively, and said bolster member and shoe having a pair of engageable wedge surfaces, respectively, sloping toward the friction surfaces and means carried by one of said members for urging said shoe surfaces against the bolster member and side frame mem-

ber surfaces respectively, one surface of at least one pair being formed of material having a static coefficient of friction, when engaged with the other surface of said one pair, not substantially greater than the kinetic coefficient of friction of said material when engaged with said other surface of said one pair.

10. A railway car truck comprising a side frame member with a friction surface, a bolster member spring-supported by said frame member, a friction shoe carried by said bolster member, and means for urging said shoe against said surface, said shoe and surface having engaged areas, one of which is formed of material having a static coefficient of friction, when engaged with the other area, not substantially greater than the kinetic coefficient of friction when engaged with said other area.

15. A railway car truck comprising a pair of relatively movable frame members, and friction means for damping relative movement therebetween comprising friction surfaces carried by respective members, one of said surfaces being formed of material having a static coefficient of friction not substantially in excess of its kinetic coefficient when engaged with the other surface, and means for urging said surfaces into engagement with each other.
